TOY WASHING MACHINE

Frank J. Goriup, McKees Rocks, Pa., assignor to
Wolverine Supply and Manufacturing Company, Pittsburgh, Pa., a corporation of Pennsylvania

Application March 16, 1933, Serial No. 661,038

3 Claims.

(Cl. 68—19)

One object which I have in view is the provision of a practical and operative miniature washing machine of the suction-cup type which will closely simulate the appearance and operation of a full size domestic washing machine.

Other novel features of construction, and also of arrangement of parts, will appear from the following description.

In the accompanying drawing, wherein I have illustrated a practical embodiment of the principles of my invention, Fig. 1 is a vertical section of one form of my improved miniature washing machine with the wringer assembly shown in elevation.

Fig. 2 is an end view on enlarged scale of the wringer assembly.

Fig. 3 is a broken plan view showing the bracket upon which the wringer assembly is mounted.

Fig. 4 is an enlarged vertical section of the suction-cup and cup-operating mechanism taken in a plane at right angles to that of Fig. 1.

Fig. 5 is an inverted plan view looking upwardly from the irregular line 5—5 in Fig. 4.

Referring to the drawing, 1 represents the tub which is supported on a suitable base 2. 3 represents the lid having a depending perimetral flange which fits down over the top of the tub.

Fixed to the side of the tub is an upper horizontal bracket 4 having a concentric arcuate perimetral edge provided with spaced notches 5. The axis of the bracket is provided with a bearing hole 6 which registers with a like bearing hole in a lower bracket 7 also extending from the tub 1.

8 represents a horizontally disposed wringer-shelf provided adjacent one end with a depending shaft 9 which extends through and is journaled in the bearing holes in the upper and lower brackets, the shelf being held elevated to clear the top bracket by means of an annular shoulder 10 on the shaft.

The rear of the shelf is provided at each end with an ear 11 and said ears have alined notches to receive the axle of the lower roll 12. One end of the axle is extended and bent to form the crank 13. 14 represents a pair of posts rising from the ends of the shelf 8, and 15 represents a pair of brackets whose bottoms are provided with outturned flanges 16 which are pierced to slip down over the posts 14. The upper ends of the brackets 15 are connected and braced by the cross plate 17 whose ends are also pierced to fit down on the posts 14. The upper ends of the posts are pierced and provided with cross pins 55 to hold the parts on the post.

The brackets 15 extend rearwardly and are provided with alined holes to receive the axle of the upper roll 18 which prevents the lower roll from jumping from its place.

The wringer shelf 4 is provided with a depending finger 19 arranged to engage one of the notches 5 in the bracket 4 and thus lock the wringer assembly against accidental rotation relative to the bracket 4. By raising the wringer assembly sufficiently to enable the finger to clear the bracket 4, the wringer may be swung into proper position to enable clothes to be wrung from the washing machine to a miniature tub or from one miniature tub to another, as may be desired. By dropping the wringer assembly the finger will be caused to drop into and engage the proper notch and thus hold the wringer-assembly in its selected position.

20 represents a rectangular frame depending from the center of the lid and having the center 20 of its cross bar pierced with a bearing hole which is alined with a similar hole in the lid 3. Journaled in said hole for both rotary and longitudinal movement is a shaft 21 whose upper end is provided with a ball 22 or other means to limit 25 the descent of said shaft.

Fixed on said shaft within the frame 20 are two parallel horizontally disposed disks 23 and 24, the upper disk 23 being provided on its under face with a concentric annular series of spaced apart 30 rounded studs 25 which may be formed by pressing down the material of the disk.

26 represents a hand crank on the outer end of a shaft 27 which extends through a hole in the lid 3 and is journaled in a bracket 28 rising from the lid and in the adjacent vertical member of the frame 20. The inner end of the shaft 27 is provided with a crank 29 whose extremity extends between the disks 23 and 24, the space between the disks being sufficient to permit the crank to 40 pass between the lower disk and the studs on the upper disk, gravity causing the upper disk to ride on the crank.

The lower end of the shaft 21 is provided with 45 a fixed yoke 30 with depending ends upon which are rigidly mounted the inverted suction-cups 31.

It is obvious that as the crank handle 26 is turned the cups 31 will alternately rise and fall and that the engagement of the studs 25 in turn 50 by the crank 29 will cause an intermittent rotation of the shaft 21. Thus the cups 31 will be reciprocated vertically and also intermittently rotated, as is the case with the suction cups of a full size washing machine.

I claim:—

1. In a toy washing machine, the combination with a tub and a lid for said tub, of a frame carried by said lid, a driving shaft extending into said frame and provided at its outer end with a handle and at its inner end with a crank, a substantially vertically disposed driven shaft slidably extending upwardly into the frame, suction cup mechanism carried by the driven shaft, a disk mounted on the driven shaft and riding on the crank, and projections on said disk arranged to be engaged by the crank when the latter is rotated whereby the rotation of said driving shaft imparts both a longitudinal reciprocating movement and a rotary movement to the driven shaft.
2. In a toy washing machine, the combination with a tub and a lid for said tub, of a frame carried by said lid, a driving shaft extending into said frame and provided at its outer end with a handle and at its inner end with a crank, a substantially vertically disposed driven shaft slidably extending upwardly into the frame, suction cup

mechanism carried by the driven shaft, and a pair of spaced apart disks mounted on said driven shaft and between which the free end of the crank fits with sufficient snugness so that the rotation of the crank causes a reciprocation of the driven shaft. 5

3. In a toy washing machine, the combination with a tub and a lid for said tub, of a frame carried by said lid, a driving shaft extending into said frame and provided at its outer end with a handle and at its inner end with a crank, a substantially vertically disposed driven shaft slidably extending upwardly into the frame, suction cup mechanism carried by the driven shaft, a pair of spaced apart disks mounted on said driven shaft and between which the free end of the crank fits with sufficient snugness so that the rotation of the crank causes a reciprocation of the driven shaft, and projections on the upper disk whereby the driven shaft is rotated by the crank. 10 15 20

FRANK J. GORIUP.
